US0D1111885S

(12) **United States Design Patent** (10) **Patent No.:** **US D1,111,885 S**
(45) **Date of Patent:** **** Feb. 10, 2026**

(54) **WATCH DIAL**

(71) Applicant: **ROLEX WATCH U.S.A., Inc.**, New York, NY (US)

(72) Inventor: **Davide Aioldi**, Geneva (CH)

(73) Assignee: **ROLEX WATCH U.S.A., Inc.**, New York, NY (US)

(**) Term: **15 Years**

(21) Appl. No.: **29/959,492**

(22) Filed: **Aug. 26, 2024**

(30) **Foreign Application Priority Data**

Mar. 5, 2024 (CH) 147908
